UNDERREAMER FOR OIL WELLS

Harry P. Miller, Taft, Calif.

Application April 7, 1941, Serial No. 387,140

3 Claims. (Cl. 255—76)

This invention relates to and has for an object the provision of an improved reaming device for oil and water wells of simple, economical and advantageous character which is applicable to drilling purposes in the same manner as conventional reamers but includes certain novel features which renders the device more efficacious than the conventional and well known types of devices.

A particular object is to provide a reaming device embodying a rotatable mandrel adapted for attachment to and for rotation by the drilling stem of a rig, and a body member coaxial with and at least partially enclosing the mandrel, or a portion thereof, and insertible in the drilling string upwardly of the drilling bit, and including a plurality of reaming tools tiltably mounted on the periphery of the body so as to swing outwardly at their upper extremities from axes at their lower extremities from normally contracted positions within the confines of the body to positions for underreaming the hole to a diameter in excess of that of the drilled hole.

An object, also, is to provide means on the mandrel for expanding the reamers to reaming position upon a slight rotation of the mandrel in the direction of rotation of the drill string and at such points to drivingly lock the mandrel and body together for common rotation.

A further object is to provide means for automatically retracting the reamers from expanded positions to positions within the body upon a reverse rotation of the mandrel.

Another object is to provide suitable stop means cooperatively arranged on the interior of the body and the exterior of the mandrel for engagement so as to limit the relative movement of the mandrel and body in opposite directions.

Whereas in the drilling of wells it is customary to provide a suitable drilling fluid usually insertible in the well through the drill pipe and reaming devices and on occasions, particularly with the use of certain apparatus, the fluid has free access to the interior of the reaming apparatus and thereby causes trouble and delays by the fouling of the mechanism with grit, sand, rust, corrosive elements, mud and the like, it is an object of this invention to provide an underreaming apparatus which is positively sealed at its top and bottom against the entrance of such fluid, and yet is arranged to permit the free flow of fluid through the unit for use in the vicinity of the drilling bit.

Frequently in the drilling of wells, old holes are redrilled or encountered and intersected by new

holes and difficulties in alining the new holes arise by reason of such obstacles, especially in cases where the old holes were not straight. It is an object, therefore, to provide in my improved apparatus a suitable means for maintaining the drilling operations in a substantially straight line, regardless of obstructions and intersections of the character named, or otherwise. To such end, I provide the underreamer body of sufficient length as to operatively support an auxiliary set of reamers in parallelism or at suitable relative angles. The auxiliary reamers are of conventional or special type and character and are arranged around the periphery of the reamer body but are spaced downwardly for a suitable distance below the underreamers and are designed to have an operative diameter substantially corresponding to that of the hole dug by the bit which is still below the auxiliary reamers. Thus, the elongated reamer body has two spaced points of bearing in the hole in addition to the bearing of the drill bit, thereby tending to maintain the reamer in a vertical position at all times during a drilling and reaming operation, regardless of obstructions encountered. Other objects may appear as the description progresses.

I have shown a preferred form of structure embodying my improvements in the accompanying drawing, subject to modification, within the scope of the appended claims, without departing from the spirit of my invention.

In said drawing:

Fig. 1 is a vertical section of my apparatus operatively positioned in a well;

Fig. 2 is a section of the same on line 2—2 of Fig. 1;

Fig. 3 is a section on line 3—3 of Fig. 1 showing the underreamers retracted;

Fig. 4 is a section on line 4—4 of Fig. 1 showing the underreamers extended;

Fig. 5 is a section on line 5—5 of Fig. 1; and

Fig. 6 is a reduced scale section of a well in which my apparatus is mounted for use and in which an old intersecting hole is about to be encountered by the drilling and reaming unit.

As shown in the drawing, the apparatus consists primarily of two main sections A and B, both generally of circular cross section. Section A is generally referred to as a mandrel and is attachable to a section of the drill stem C as by means of an externally threaded collar 1 which is screwed into a correspondingly threaded recess 2 of the mandrel. The body section B is coaxial with the mandrel and is bored at 3 to rotatably receive the lower portion of the mandrel.

and is also counterbored at 4 to receive a reduced extension 5 of the mandrel, as shown in Fig. 1, thereby centering the body and mandrel for operation.

It will be noted that both the mandrel and body are correspondingly bored at 6 and 7, respectively, to receive a pipe 8 which is continuous from a point of communication with the drill stem collar 1 to a point of communication with a similar collar 7' on drill bit D. Bit D is attached to body B by means of collar 7'.

Mandrel A and body B are rotatably connected and also held against longitudinal disconnection by means of a pair of sets of ball bearings 9 and 10 which run in external grooves 11 and 12, respectively, formed on the periphery of the mandrel and aligned internal grooves 13 and 14, respectively, formed on the interior of body B, thereby providing frictionless bearings between the two main members of the apparatus. The balls of the two sets of bearings may be inserted in their grooves or removed therefrom as by means of apertures 15 in the annular wall of the body which threadedly hold plugs 16, so that the balls may be inserted or removed, one after another, when said plugs are removed, and may be retained in operative positions when the plugs are screwed into the apertures.

The upper end of pipe 8 has a flange 17 overlying the bore 6 of the mandrel and seated in the bottom of a counterbore 18. A packing gland is detachably held in the counterbore 18 and includes one or more packing rings 19 and a compressing member 20 which is threaded into counterbore 18 so as to confine and compress the packing rings between the flange 17 and member 20 around the upper end of pipe 8, so as to prevent leakage of a drilling fluid supplied through drill stem C around the pipe 8.

The upper portion of body B having the bore 3 in which the lower portion of the mandrel is rotatably mounted is internally threaded at 21 to receive a correspondingly externally threaded extension 22 of a closure member 23 for the upper end of the body. Packed rings 24 and 25 are adapted to be compressed between internal shoulders of the body and the lower end of extension 21 for sealing the body against the entrance to the interior thereof of the drilling fluid. The closure 23 is tapered from its lower end to its upper end gradually so as to avoid shoulders or abutments on the exterior of the reamer apparatus, as is customary in well-drilling practice.

The lower end of the body is also sealed against the entrance of the drilling fluid, as by means of a counterbore 26 in which one or more packing rings 27 are compressed between the end of the counterbore and a plug 28 which is threaded into the end of the body.

Body B has a plurality of vertically or angularly disposed recesses 29 formed on the periphery thereof for adjustably supporting reamer units E, of which there may be any desired number depending upon the size and character of the well—the form of device shown illustrating but three of such units.

Each underreaming unit E includes a U-shaped bracket having a flat back portion 30, upper and lower bearing portions 31 and 32, respectively, and a rotatable reaming tool 33 supported on a shaft 34 and suitably fluted, ribbed or otherwise formed for underreaming the well following the bit D downwardly in the hole H and thereby providing an enlarged and reamed hole H'.

The lower bearing portions of the underreamers are pivotally supported on body B by means of horizontal pins 35 so that the upper extremities of the reamers may be swung outwardly to a desired extent under the influence of and when the mandrel is rotated by the drill stem, as hereinafter explained.

The reamer supporting brackets have extensions 36 projecting above the portions 31 which are engaged by flat springs 37 attached at their upper ends to the body and having their lower ends resting against the portions 31, for tensioning the reamers so as to normally retract the reamers from extended to retracted positions within the recesses 29.

The lower end of the mandrel A has a cam 38 thereon with spiral segments 39 adapted to engage the inner surfaces of the reamer brackets, as shown in Figs. 1 and 4, for extending the reamers to operative position in the well when the mandrel has been rotated sufficiently. Normally, the reamer supports will engage the low dwells of said cams and at such times, the reamers will be within the limits of the hole H but when operations are instituted the mandrel will be rotated by the drill stem until the cam segments will have extended the reamers 33 at their upper ends to a required extent for an underreaming operation, and at such times the relative rotation of the mandrel and body will have been stopped due to the engagement of lugs 40 on the mandrel with lugs 41 on the interior of the body. Other lugs 42 on the mandrel by reason of their engagement with lugs 43 on the interior of the body prevent the retraction of the mandrel in the body beyond a predetermined extent and serve to establish a normal relationship between the mandrel and body before the institution of an underreaming operation.

Above each of the reaming units E, I provide on the exterior of the body B vertical ribs 44 of suitable width to cover the upper ends of the reamers when they are in retracted position in order that the tool may be lowered into the drilled hole H made by the bit D. In this connection, it may be understood that the overall diameter of the tool when the reamers are retracted does not exceed the diameter of the bit D.

Spaced suitably below the underreamers and mounted on the body B is a set of auxiliary reamers F corresponding to or more or less in number than the underreamers and which have trunnions 45 and 46 at their tops and bottoms, respectively, for rotatably supporting the auxiliary reamers on the body and in recesses 47 formed peripherally on said body. The auxiliary reamers are fixed in position and serve to ream the hole H made by the bit D and at the same time serve as an extra bearing in the hole for the assembled tool, whereby the tool may be directed in a predetermined course, in cooperation with the bit and the underreamers.

Preferably, the auxiliary reamers are disposed at different angles, though not necessarily, in order that the hole made by the bit may be thoroughly scavenged and smoothed in its downward course. As shown in Fig. 6, the combination of the two sets of reamers and the bit serve to direct the course of the tool in a substantially true vertical course, even when old divergent holes H' are encountered, or in the event of other obstructions.

The underreamer units E are sealed against the entrance of the drilling fluid by means of sheets of leather or the like, as at 48, attached

to the backs of the portions 30 of the underreamer supporting brackets and in such a manner that the edges thereof will wipe the margins of the recesses 29 and prevent leakage of the drilling fluid into the interior of the body B through said recesses, and around the joint between the body and mandrel in the vicinity of the cam 38.

Thus, as the tool progresses in its downward movement in the ground the bit digs the hole, the series of auxiliary reamers sizes the hole and the series of underreamers enlarges the hole to a desired size for the reception of a well casing, as in other types of reamers.

The combination of the two sets of reamers mounted on a single body tends to straighten the hole as nearly as possible and the transition from operative reaming condition to a non-reaming condition is readily established by retracting the mandrel in the body sufficiently to permit the tension of springs 37 to retract the underreamer units to an overall diameter comparable to the hole reamed by the auxiliary reamers. Hence, the tool in its completeness may be inserted in and removed from a well with facility.

The interior of body B and also of mandrel C is completely packed with grease in order that ample lubrication may be provided between said members for relative rotation thereof and at the same time, the presence of grease in any cavities or chambers of said members will resist the entrance of the drilling fluid particularly around the underreamers E and the mountings therefor.

What I claim is:

1. An underreamer for wells comprising: a body, a mandrel rotatably mounted in said body, said body having a plurality of recesses formed on the periphery thereof, a chamber being formed in the body near the lower end of the mandrel arranged for communication with the upper extremities of said recesses, a plurality of rotatable underreamers pivotally supported in the lower extremities of said recesses for extension above the axes thereof outwardly from the body and

having portions extending into said chamber, and means on said mandrel engageable with the extended portions of the reamers for extending the reamers into operative positions.

5 2. An underreamer for wells comprising: a body, a mandrel rotatably mounted in said body, said body having a plurality of recesses formed on the periphery thereof, a chamber being formed in the body near the lower end of the mandrel 10 arranged for communication with the upper extremities of said recesses, a plurality of rotatable underreamers pivotally supported in the lower extremities of said recesses for extension above the axes thereof outwardly from the body and having portions extending into said chamber, and means on said mandrel engageable with the extended portions of the reamers for extending the reamers into operative positions, and means on the periphery of the mandrel and on the bore 15 of the body for limiting the relative movement of the body and mandrel, for the purpose described.

20 3. An underreamer for wells comprising: a body having a major bore in its upper portion and a minor bore in its lower portion, a mandrel 25 rotatable in said major bore and having a bore corresponding to the minor bore of the body, a drill stem attachable to the upper end of the body, a drill bit attachable to the lower end of the body, a pipe for drilling fluid held in the minor bore of the body and in the mandrel and connected with said drill stem and said bit for delivering a fluid from said stem to said bit, a plurality of 30 inclinable and extensible reamers carried on the exterior of said body, means on the lower portion of said mandrel operatively engageable with said reamers for extending the same to operative position, means confined between the periphery of the mandrel and the major bore of the body for preventing the longitudinal separation of the body and mandrel and including corresponding 35 annular grooves, and rotatable elements held in said grooves adapted to be inserted and removed through radial apertures in the body.
